DESIGN FOR A COMB

John Denman Dean, Tolworth, England

Application July 19, 1935, Serial No. 57,748

Term of patent 7 years

To all whom it may concern:

Be it known that I, John Denman Dean, a subject of the King of Great Britain, and resident of Tolworth, in the county of Surrey, England, have invented a new, original, and ornamental Design for a Comb, of which the following is a specification, reference being had to the accompanying drawing forming part thereof.

Figure 1 is a perspective view of one side of the comb showing the new design.

Figure 2 is a perspective view looking at the other side of the comb shown in Figure 1.

I claim:

The ornamental design for a comb, as shown.

JOHN DENMAN DEAN.
